UNITED STATES PATENT OFFICE

CLARENCE G. WOOD, OF MUNCIE, INDIANA, ASSIGNOR, BY MESNE ASSIGNMENTS, TO
AUTO PRIME PUMP COMPANY, OF CLEVELAND, OHIO, A CORPORATION OF OHIO

CENTRIFUGAL PUMP

Application filed June 24, 1926. Serial No. 118,150.

My invention relates to improvements in centrifugal pumps and has for one of its objects the production of a pump of this character having a higher efficiency than has heretofore been obtained with centrifugal pumps.

Another object of my invention is to provide a pump which from a manufacturing standpoint may be constructed more readily and cheaply than this type of pump has heretofore been built.

For the purpose of disclosing my invention I have illustrated one embodiment thereof in the accompanying drawing in which

Fig. 1 is a side elevation partly in section 15 of a pump embodying my invention;

Fig. 2 is a sectional view on the line 2—2 of Fig. 1;

Fig. 3 is a detail section through the impeller channel;

Fig. 4 is a similar section through the intake ports;

Fig. 5 is a similar section through the outlet port;

Fig. 6 is a perspective view showing one of 25 the channel rings;

Fig. 7 is a perspective view of the opposite ring, and

Fig. 8 is a side elevation of a portion of the impeller.

In the embodiment illustrated I provide a cylindrical casing 1 which is preferably formed from a single casting, which casing has a peripheral inlet 2 extending through a neck 3 which provides means for connecting the inlet with the inlet pipe. A similar neck 4 having an outlet 5 is provided on the casing. One side of the casing is open and this open side is adapted to be closed by a head or cover 6 secured to the casing by suitable cap screws 7.

The casing is adapted to receive a pair of rings 8 and 9 which mate together when assembled in the casing and form an annular impeller channel. To this end the ring 9 is

provided with an annular flange 10 at its periphery and with an inner annular flange 11, the two forming a channel 12 comprising a portion of the impeller channel. The height of the flange 11 is less than that of the flange 10 to the extent of the thickness of the im-

peller wheel so that the flange 10 over-hangs the flange 11.

At one point in the periphery of the ring in a position where it will coincide with the opening 5 there is provided a channel or cut-away portion 13 in the flange 10 to provide for the discharge opening in the impeller channel and adjacent this opening and in a position where it will coincide with the intake opening 2 the flange 10 has extending therethrough and meeting with the channel 12, an inlet port 14. At the point where this port is formed the flange 10 is thickened as at 15 to reduce the size of the channel 12 so that at this point the distance between the inner face of the flange 11 and the inner face of the flange 10 is about equal to the length of an impeller blade. The portion 15 thus blocks direct radial connection between the inlet passage 2 and the impeller blades, forcing flow through the inlet to the impeller blades axially of the impeller. This is important because normal rotation of the impeller tends to throw the fluid radially of the impeller and if there is direct radial connection between the spaces between the impeller blades and the inlet, the impeller blades will be acting directly against inflow, thus creating eddy currents at the point of inflow to the impeller blades, which would materially lessen efficiency.

The ring 8 is adapted to mate with the ring 9 and is provided with an annular flange 10^a to coincide with the flange 10 and a flange 11^a to coincide with the flange 11, the two flanges 11^a and 10^a forming, between them, an annular channel 12^a which coincides with the channel 12 to complete the impeller channel. This ring like the ring 9 is provided with an outlet channel 13^a communicating with the channel or recess 13 and with an inlet port 16 meeting the channel 12^a. In each of the rings there is provided in the channel 12 to separate the intake and delivery ports, a web 17 or 17^a.

The impeller wheel preferably comprises a hub 18 having radial spokes 19 carrying at their outer ends the rim 20. The impeller blades 21 are mounted on this rim, being preferably cast integrally therewith and the diameter of the wheel is such that these blades 100

lie wholly within the impeller channel the blades however being slightly shorter than the height of the channel except at the point where the flange 10 is thickened at 15 where the height of the channel is substantially that of the impeller blades. These blades 21 have the face thereof curvedly inclined from the base to the end thereof, that is, the impeller blades curvedly incline away from their direction of rotation. The impeller wheel is mounted on a shaft 22 passing through a stuffing box bearing 23 in the side of the casing and having its outer end mounted in an outboard bearing 24. When the parts are assembled the rings are clamped between the head 6 of the casing and the side thereof and snugly fit the casing. These rings are held against relative movement with respect to one another and with respect to the casing by a pin 25 passing through the rings and into the casing.

By the above construction the fluid enters the impeller chamber at the periphery thereof through the port 2 and the ports 14 and 16 being delivered however transversely of the impeller blades by which it is picked up and, traversing the impeller channel, is delivered through the ports 13 and 13^a which constitute the outlet port of the channel and through the outlet port 5 of the casing. During its traversing movement through the channel the liquid repeatedly comes in contact with the impeller blades whereby the efficiency of the pump is increased and due to the fact that the impeller blades are curved away from the direction of rotation a distinct radial impelling force, in addition to the centrifugal action, is imparted to the fluid at the outlet port.

I claim as my invention:

40 1. In a centrifugal pump the combination with a casing, of a pair of removable rings mounted in said casing and formed to provide an annular impeller channel, an impeller wheel operating in said casing, impeller blades at the periphery of said wheel operating in said channel, said channel having peripheral intake ports arranged to deliver fluid into said channel and into contact with said blades, and means blocking direct radial flow between the inlet and the impeller wheel pockets.

55 2. In a centrifugal pump the combination with a casing, of a pair of removable rings mounted in said casing and formed to provide an annular impeller channel, an impeller wheel operating in said casing, impeller blades on the periphery of said wheel operating in said channel and having their faces inclined away from the direction of rotation of said impeller, said channel having an intake port for delivering fluid into the pockets between said blades in a direction substantially parallel with the axis of the impeller 60 wheel, and means blocking direct radial flow

between the inlet and the impeller wheel pockets.

3. In a centrifugal pump the combination with a casing, of a pair of removable rings mounted in said casing and formed to provide an annular impeller channel therein, an impeller wheel operating in said casing, impeller blades on the periphery of said wheel projecting into said channel, said channel having an intake port for delivering fluid 70 into the pockets between said blades in a direction substantially parallel with the axis of the impeller wheel, and means blocking direct radial flow between the inlet and the impeller wheel pockets. 75

4. In a centrifugal pump the combination with a casing, of a pair of removable rings mounted in said casing and formed to provide an annular impeller channel therein, an impeller wheel, blades mounted at the periphery 80 of said wheel and projecting into said channel and having their faces inclined away from the direction of rotation of the wheel, said channel having peripheral intake ports arranged to deliver fluid to the pockets between said blades from opposite sides of the impeller and in a direction substantially parallel with the axis of the impeller wheel, and means blocking direct radial flow between the inlet and the impeller wheel pockets. 85

5. In a centrifugal pump the combination with a casing having an intake port and an outlet port, of a pair of mating rings fitting within said casing and having their adjacent faces formed to provide an annular impeller channel, said rings being provided with intake and discharge ports coinciding with the inlet and discharge openings of the casing, an impeller wheel within said casing and impeller blades mounted on the periphery of 100 said wheel projecting into the annular channel formed by said rings, and means blocking direct radial flow from the inlet to circumferential portions of the spaces between the impeller blades. 105

6. In a centrifugal pump the combination with a casing having inlet and discharge ports therein, of a pair of mating rings fitting within said casing and having their adjacent faces provided with annular channels to form, 110 when rings are assembled, an impeller channel, the periphery of said rings being provided with inlet openings arranged to discharge the fluid into the impeller channel and arranged to coincide with the inlet opening of the casing and with peripheral outlet openings coinciding with the outlet opening of the casing, an impeller wheel in said casing and impeller blades mounted on the periphery of said wheel and projecting into 115 said impeller channel, and means blocking direct radial flow from the inlet to circumferential portions of the spaces between the impeller blades, said means cooperating with 120 said inlet openings to cause fluid to flow into 125 said inlet openings to cause fluid to flow into 130

contact with said blades in a direction substantially parallel with the axis of said rings.

In witness whereof, I, CLARENCE G. Wood, have hereunto set my hand at Muncie, Indiana, this 18th day of June, A. D. one thousand nine hundred and twenty-six.

CLARENCE G. WOOD.
